(57) **CLAIM**

The ornamental design for a leaf ceiling fan blade, as shown and described.

DESCRIPTION

FIG. 1 is a top perspective view of a leaf ceiling fan blade, showing the new design;

FIG. 2 is a top view with the bottom view being a mirror image;

FIG. 3 is a side view with the opposite side being a mirror image;

FIG. 4 is a front view;

FIG. 5 is a rear view; and,

FIG. 6 is a cross-sectional view across a portion of the width of the leaf ceiling fan blade taken along line 6—6 in FIG. 2.

The broken line showings of FIGS. 1, 2, and 5 are for the purpose of illustrating unclaimed portions of the leaf ceiling fan blade and form no part of the claimed design.
